UNITED STATES PATENT OFFICE

2,517,340

PRESS FOR MOLDING TILE

Jamie O'Hara, Mexico City, Mexico

Application June 21, 1948, Serial No. 34,220

1 Claim. (Cl. 25—84)

1

This invention relates to presses for molding tile, particularly multi-colored decorative tile, and more especially it relates to manually-controlled presses which may be operated from opposite sides.

One important object of this invention is to provide a novel construction of a press for molding tile and the like, wherein two workmen can operate the press alternately from opposite sides of the machine. These men, being the master tile makers, each make up the tile material in the mold, place the mold in the press, and operate it for the required pressure and remove the mold, each man working alternately. By the use of this invention, two men can make the tile and two men strip the tiles and function on a continuous operational basis.

Another important object of the invention is to provide a construction of a press for this purpose, wherein there exists a flat table, over which molds containing the material to be compressed may be slid into position for compressing action, and after compression of such material, it may be removed by a simple sliding movement.

A third object of the invention is to provide a press for the production of tiles and the like, whereby tiles, both floor and wall, may be fabricated on a production basis.

A still further object of the invention is to provide a press for tiles which may be readily used for the forming of such articles with an ornamental face and/or ornamental conformation.

Also, this invention contemplates the production of a novel press adapted to effect the molding of articles of any desired thickness within the capacity of the press.

With the above and other objects in view, as will be presently apparent, the invention consists in general of certain novel details of construction and combination of parts hereinafter fully described, illustrated in the accompanying drawings, and particularly claimed.

The novel features that are considered characteristic of the invention are set forth with particularity in the appended claim. The invention itself, however, both as to its organization and its method of operation, together with additional objects and advantages thereof, will best be understood from the following description of a specific embodiment when read in connection with the accompanying drawings, wherein like parts are indicated by like reference characters throughout, and in which:

Figure 1 is a cross sectional view taken on a vertical plane centrally through the press;

Figure 2 is a cross sectional view taken on the line 2—2 of Figure 1;

Figure 3 is a plan view of the press; and

Figure 4 is a perspective view of the press.

5 In the embodiment of the invention, as shown in the drawings, there is provided a base or standard 10, on which the whole device rests. On the base 10 is supported the hydraulic cylinder 11. The body portion of this cylinder is, of course, 10 thick enough to withstand the pressures necessary for producing the output. At the center of the body 11, there is provided a bore 12, and this bore is continued up through an annulus 13 rising from the center of the body 11. At the upper 15 end of the annulus, there is secured by any suitable means (not shown) a closure 14 provided centrally with a packing box 15.

20 Mounted on the top of the annulus 13 is a table 16 having a centrally disposed opening 17. The table 16 has recesses 16a at opposite sides to enable the two operators employed in working the press to stand closer to the center of the table so that they may easily handle the molds. Fitting the opening 17 is a presser head 18 which is carried by the upper end of a piston rod 19 passing through the stuffing box 15 and having at its lower end a piston 20 fitting the bore 12, and as usual, provided with proper packing rings. Surrounding the rod 19 between the piston 20 and the closure 14, is a coiled compression spring 21, which 25 constantly urges the piston 20 downwardly in the bore 12. At this time, it is to be observed that when the piston is in its lowermost position, the top of the head 18 will be flush with the top of the table 16, so that molds containing unpressed material can be readily slid from the table onto the pressure head. Also, it will be noted that the molds may as readily slide off the pressure head onto the table when loose on the pressure head.

30 Projecting from the body 11 are ears 22, on which are fixed heavy bolts 23. These bolts 23 extend upwardly and carry what may be termed a crown member 24, which is adjustable toward and from the table by nuts 25 on the bolts 23, the bolts 23 also being adjustable relative to the ears 22.

35 The mold, according to the preferred form, 40 comprises a peripheral member 25a split at opposite sides, as at 26, and held together by clamps 27, the construction of which is obvious and 45 essentially has no special reference to this press. Also, on the upper member 24, there is provided a die 28, which may be of any preferable form, either to provide an opening in the tile or to carry 50 a facing member therefrom.

On one side of the device there is provided a fluid inlet pipe 29 leading to the bottom of the bore 12 and from this pipe leads a duct 30 to a pressure gauge 31, by which the pressure within the bore 12 may be controlled.

In operation, the workman on one side of the table takes a prepared mold and places it on the table over the head 18. The valve 32 is then opened to admit fluid under pressure to the cylinder, which causes the head to rise and carry the mold up until the part 12 engages the member 28 and the material in the mold is properly compressed, preferably at four to six pounds per square inch, as evidenced by the pressure gauge 31. The valve 32 is now operated to bleed the cylinder so that the head 18 drops to the level of the table, whereupon the mold is removed and the workman at the opposite end of the table repeats the same operation.

Although a certain specific embodiment of the invention has been shown and described, it is obvious that many modifications thereof are possible. The invention, therefore, is not to be restricted except insofar as is necessitated by the prior art and by the spirit of the appended claim. 20

What I claim is:

A molding machine comprising a base formed on its top surface with a cylinder, the upper edges of the cylinder having a vertical flange to provide a seat, a cover fitted in the seat, said 30 cover having a central opening, a piston in the cylinder from which extends a piston rod projected through the opening in the cover, a table

having a centrally disposed opening above the cylinder, a depending annular flange around the opening in the table, the lower edge portion of the flange having an annular seat to engage and fit over the vertical flange on the cylinder, a pressure head on the upper end of the piston rod which head when in normal lowered position is flush with the top of the table, a frame rising from the table including a cross bar extending across the vertical plane of the pressure head, a die depending from the cross bar in vertical alignment with the piston rod, a spring interposed between the top of the piston and the cover tending to return the piston to normal position with the pressure head flush with the top of the table, a pipe to supply pressure to the bottom of the cylinder, and a pipe to exhaust the pressure from the top of the cylinder.
